UNITED STATES PATENT OFFICE.

GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

ELECTRIC SWITCH.

1,347,308.

Specification of Letters Patent.

Patented July 20, 1920.

Application filed January 15, 1916. Serial No. 72,324.

To all whom it may concern:

Be it known that I, GEORGE B. THOMAS, a citizen of the United States of America, and residing at Bridgeport, in the county of 5 Fairfield and State of Connecticut, have invented a certain new and Improved Electric Switch, of which the following is a specification.

My invention relates to electric switches 10 and particularly to a combined switch mechanism by which a plurality of circuits may be simultaneously or individually controlled.

In the accompanying drawings,

Figure 1 is a broken side elevation of a 15 switch in which my invention is embodied in one form;

Fig. 2 is a section on the line 2—2, Fig. 1;

Fig. 3 is a section on the line 3—3, Fig. 2;

20 Fig. 4 is a detached perspective of portion of the switch-operating mechanism; and

Fig. 5 is a diagram of one wiring system for the switch.

The present switch is particularly designed for controlling a plurality of circuits, such as lighting circuits in residences or the like where it is desired to switch on or off any one or more of a plurality of different groups of lamps in a single room 25 or hall. As a compact and efficient device for this purpose, I provide a plurality of correlated switch mechanisms mounted within a single switch base and of a size and construction such that it may be arranged 30 within a single gang outlet box of standard construction.

In the form here shown, the device comprises a cup-shaped insulating body 10, the open top of which is spanned by a yoke 40 piece 11 by means of which the switch body may be mounted within an outlet box in well understood manner. At its four upper corners are depressed ledges 12, 13, 14, 15 on which are seated wire terminals 16, 17, 45 18 and 19. The interior of the body is divided roughly into two switch chambers 20 and 21 by a barrier 22 which extends from one wall of the receptacle partially across the interior of the latter about midway between the ends. Within the switch chamber 50 20 is arranged a pair of switch terminals 23 and 24, the former comprising the offset lower end of the strap which forms the base of the wire terminals 16. To this terminal

the lead from the main is attached. The 55 other contact 24 is connected to the wire terminal 19 by a strap 25 let into the lower face of the insulating body and extending between the terminal 24 and the base of the wire terminal 19, being respectively connected to these terminals by the screw bolts 26 and 27 piercing the bottom of the receptacle. Within this chamber 20 is also mounted a suitable switch mechanism of the single pole type comprising a switch blade 28 adapted to span the switch terminals 23 and 24 and make or break the circuit between the latter.

Within the other switch chamber 21 are arranged several switch terminals 29, 30, 70 31, and 32, the last two terminals constituting a bow-shaped strap presenting the terminals 31 and 32 at different levels in the switch chamber. It is connected to the wire terminal 17 by a strap 33 let into the lower 75 face of the bottom of the receptacle and extending between the switch terminal and the wire terminal 17 to which it is respectively connected by the screw bolts 34 and 35. The switch terminal 30 comprises the offset lower end of the strap which forms the base for the wire terminal 18. Terminal 29 is integral with the base of the terminal 24 and thus leads the current from switch chamber 20 to switch chamber 21 when the 80 switch blade 28, in the chamber 20, spans the switch terminals 23 and 24.

Within the switch chamber 21 is arranged a switch having a plurality of switch blades 36 and 37 lying respectively at the levels 90 of the terminals 31 and 32, but electrically connected together. It is obvious that when the switch blade 28 is "on", current is led through the terminal 24 to the wire terminal 19, thus closing the circuit through lamp group connected to the latter. If it is desired to bring into circuit the second lamp group connected to the terminal 18, the switch in chamber 21 is moved to the position which follows that shown in Fig. 2, so that the 100 terminals 29 and 30 are spanned by the switch blade 37. In this position the switch blade 36 is in contact with the upper terminal 31, connected to the wire terminal 17, so that the group of lamps connected to the 105 latter is also in circuit. If the switch in chamber 21 be now advanced another step, the switch blade 36 is brought to a position

in which it overlies the terminal 30 and is out of contact therewith, while the circuit is established between the lower contact 32, on the one hand, and the switch terminal 29, on the other hand, by the switch blade 37. The succeeding position of the switch is that shown in Fig. 2 in which the current is entirely cut off from the switch now by reason of the fact that the blade 36 overlies the terminal 29 and is out of contact therewith, thus leaving in circuit only the group of lights connected through the terminal 19. Obviously by various other arrangements of switch terminals in chamber 21, and corresponding alterations in the shape and arrangement of the switch blades in this chamber, various other combinations of lights may be made to suit the needs of the particular installation.

20 While any suitable switch mechanism may be employed to accomplish the result obtained, I have shown in the present application of my invention a novel arrangement which is both compact and efficient. The 25 switch mechanisms of both chambers are alike and it suffices to describe the construction with relation to only one. In its general form the switch is of the push button type with spiral drive. The connection between the ratchet sleeve 38 and the switch spindle 39, however, in the present construction, comprises certain features of novelty. The ratchet sleeve, which as usual is provided with spiral grooves 40, engaged 30 by the threads 41 in the reciprocating push button 42, carries at its lower end a ratchet 43 which may be formed in one therewith by cutting the ratchet teeth from a peripheral flange at the end of the sleeve. Fast 35 on the spindle 39 is mounted a disk 44 having at one side a raised marginal flange 45. Adjacent the opposite margin of the disk is pivoted at 46 a dog 47, the nose of which engages the ratchet teeth 43 of the 40 sleeve 38. The dog is held in engagement with the ratchet 43 by means of a leaf spring 48 bearing against one end of the dog and lying at its other end against the raised flange 45 on the disk 44. A tongue 49, adjacent one end of the spring, passes 45 through a hole 50 in the disk and is turned over beneath the latter, thus anchoring the spring in position on the disk. A group of downwardly projecting tongues 51 are struck 50 from the body of the disk and afford means for engaging the upper end 52 of the switch spring 53 which extends between the disk and the plate 54 which carries the switch blades. The usual cam 55 on the spindle 55 shifts the detent 56 out of engagement with the stop plate 57 in well understood manner. The stop plate 57, for each switch, is secured to a common base plate 58 arranged in the bottom of the receptacle and secured 60 by means of screw bolts 59 and 60 which

pierce the bottom of the receptacle and take into tapped holes in end lugs in the base plate. The guide pins 61 for the push buttons 42 are carried by the yoke 11 in both instances.

As a matter of convenient arrangement and secure mounting for the terminals 24 and 29, I form in one wall of the chamber a vertical groove 62 into which fits the combined terminal 24-29 so that a securing screw 26 is sufficient to hold the terminal against displacement under the action of the several switch blades. A similar construction is employed for the combined switch terminals 32 and 31 in the opposite wall of the receptacle, a seating recess 63 being provided for this purpose.

Various modification of construction will readily occur to those skilled in the art without departing from what I claim is my invention.

I claim as my invention:

1. An electric switch device, comprising a cup-shaped insulating receptacle, a yoke piece extending across the top thereof, a pair of switches mounted in series within the receptacle, independent push buttons for actuating the switches and guide pins extending at right angles to the yoke piece and arranged lengthwise thereof on opposite sides of each push button.

2. An electric switch device, comprising a cup-shaped insulating receptacle adapted to be mounted within a standard single switch box, a pair of switches mounted with in the receptacle in series, a main line switch terminal for one of said switches, a plurality of branch line terminals for the other of said switches, together with a switch terminal common to the blades of both switches and serving to connect the same electrically in series, substantially as described.

3. An electric switch device, comprising a cup-shaped insulating receptacle adapted to be mounted within a standard single switch box, a pair of switches arranged in said receptacle, means for operating the same independently of each other and conductors serving to connect the same in series, one of said switches having a terminal for a main line connection and being a single pole switch, the other switch having switch terminals for a series of lamp circuits and comprising a switch mechanism adapted to make various connections with said terminals in successive positions of the switch, for the purpose described.

4. An electric switch device comprising a cup-shaped insulating receptacle adapted to be mounted within a standard single switch box, a pair of independently operated switches arranged at opposite ends of said receptacle, a main line switch terminal for one of said switches, a series of branch line

terminals for the other of said switches, the latter having means for making various connections with said branch line terminals for the purpose specified, together with a switch 5 terminal common to both switches for connecting the same in series, substantially as described.

5. An electric switch comprising a cup-shaped insulating receptacle adapted to be 10 mounted within a standard single switch box, a pair of independently operated main and distributing switches arranged at opposite ends of the receptacle, wire terminals mounted at more than two of the corners of the 15 receptacle, a switch contact electrically connected to one of said wire terminals and

coöperating with the main switch mechanism, a series of switch contacts electrically connected respectively with the remaining wire terminals and coöperating with the 20 distributing switch mechanism, together with switch contacts serving to establish a series connection between the switches, for the purpose described.

In testimony whereof I have signed my 25 name to this specification, in the presence of two subscribing witnesses.

GEORGE B. THOMAS.
